ABSTRACT: This invention relates to mold forms for, and a method of, casting a lining in a conduit and, more particularly, to an improved mold form for casting refractory linings in the conduit sections of a blast furnace.

The form for casting a lining in a conduit having a predetermined nonlinear conduit shell has a form shell substantially similar in contour to the conduit shell, and a locating member secured to one end of the conduit shell and to the form shell to support the form shell, to align the form shell with the conduit shell to define a lining cavity between the conduit shell and the form shell, and to close the one end of the lining cavity.

The method of casting a lining in a conduit having a predetermined nonlinear conduit shell includes the steps of securing a form shell to one end of the conduit shell to support the form shell, to align the form shell with the conduit shell to define a lining cavity between the conduit shell and the form shell, and to close the one end of the lining cavity, and casting a refractory lining in the lining cavity.

FORM FOR CASTING A LINING IN A CONDUIT

BACKGROUND OF THE INVENTION

Heretofore, in the installation of a refractory lining in the conduit section between the bustle pipe of a blast furnace and the blow pipe, it has been customary to utilize fixed welded metal forms to cast such refractory lining. These fixed forms had to be destroyed by torch burning or the like and were not readily collapsible or reusable.

OBJECTS OF THE INVENTION

It is the general object of this invention to avoid and overcome the foregoing and other difficulties of and objections to prior art practices by the provision of an improved method of, and an improved form for, casting linings in a conduit system, which improved form:

1. is simple and rugged in construction;
2. is readily collapsible and removable from the conduit system after the casting operation; and
3. is reusable in the conduit system during a long operational life for repeated relining of the conduit system.

BRIEF SUMMARY OF THE INVENTION

The aforesaid objects of this invention, and other objects which will become apparent as the description proceeds, are achieved by providing an improved method of, and form for, casting a lining in a conduit having a predetermined nonlinear shell. The form has a form shell substantially similar in contour to the conduit shell and a locating member secured to one end of the conduit shell and to the form shell to support the form shell, to align the form shell with the conduit shell to define a lining cavity between the conduit shell and the form shell, and to close the one end of the lining cavity.

The method of casting a lining in a conduit having a predetermined nonlinear conduit shell includes the steps of securing a form shell to one end of the conduit shell to support the form shell, to align the form shell with the conduit shell to define a lining cavity between the conduit shell and the form shell, and to close the one end of the lining cavity, and casting a refractory lining in the lining cavity.

BRIEF DESCRIPTION OF THE SEVERAL VIEWS OF THE DRAWINGS

For a better understanding of this invention reference should be had to the accompanying drawings, wherein like numerals of reference indicate similar parts throughout the several views and wherein:

FIG. 1 is a fragmentary sectional view of a bustle pipe, a blow pipe, a tuyere stock for connecting the bustle pipe to a blow pipe, the tuyeres on the end of the blow pipe and a portion of brickwork of the blast furnace adjacent the tuyere;

FIG. 2 is a fragmentary sectional view of the upper portion of the tuyere stock showing the upper section of the form secured to such upper portion;

FIGS. 2A-2D are sectional views along the lines IIA-IID of FIG. 2 in the direction of the arrows;

FIG. 3 is a fragmentary sectional view of the middle portion of the tuyere stock showing the middle form shell secured to such middle portion;

FIGS. 3A-3E are sectional views taken along the lines IIIA-IIIID, etc., of FIG. 3 in the direction of the arrows;

FIG. 4 is a fragmentary sectional view of the lower portion of the tuyere stock showing the lower form shell secured to such lower portion;

FIGS. 4A-4G are sectional views taken along the lines IVA-IVD, etc., of FIG. 4 in the direction of the arrows; and

FIG. 4H is a side elevational view of a forming jig used to shape the upper portion of the cast refractory lining in the lower form shell.

Although the principles of this invention are broadly applicable to the casting of a lining in a hollow body, this invention is particularly adapted for use in conjunction with the

casting of a refractory lining in a conduit portion of a blast furnace and hence it has been so illustrated and will be so described.

DETAILED DESCRIPTION

With specific reference to the form of this invention illustrated in the drawings, and referring particularly to FIG. 1, a bustle pipe of a blast furnace (not shown) is indicated generally by the reference numeral 10.

- 10 For the purpose of permitting the discharge of a heated fluid, such as air, from the bustle pipe 10, such bustle pipe 10 is provided with an outlet 12 (FIG. 1). So that such heated air may be conducted to a tuyere 14 (FIG. 1) mounted on brickwork 15 of the blast furnace (not shown), a tuyere stock 16 (FIG. 1) extends from such outlet 12 through a blowpipe 18 (FIG. 1) to the tuyere 14. As shown in FIG. 1, the tuyere stock 16, has an upper portion or upper conduit shell 16a which fits into the outlet 12 of the bustle pipe and terminates in a flange 16a1; a middle portion or middle conduit shell 16b having an upper flange 16b1, (which flange 16b1 is bolted through a filler ring 19 to the flange 16a1) and terminates in a spherical ring 16b2; and a lower portion or lower conduit shell 16c extending from a spherical seat 16c1 (in engagement with the spherical ring 16b2) to a lower flange 16c2. So that a peep-sight may be provided into the tuyere 14, the lower portion 16c of the tuyere stock 16 is provided with a peep-sight inlet 16c3 (FIG. 1) in alignment with the blow pipe 18 and tuyere 14. The lower flange 16c2 (FIG. 1) of the lower section 16c is bolted through a filler ring 19a to an adjacent flange seat 18a associated with the blowpipe 18, which blowpipe 18 of course extends to the adjacent tuyere 14.

In order to provide the tuyere stock 16 with a castable refractory lining 20 (FIG. 1), suitably for example of Glasrock 35 5820 castable refractory manufactured by the Glasrock Products Inc., Atlanta, Georgia, an improved collapsible, reusable form (FIGS. 1, 2, 3, 4) of this invention is employed.

This form for casting the refractory lining 20 into the tuyere stock 16 (which has a predetermined nonlinear shell or contour) has (similar to the tuyere stock 16) three sections, an upper section or upper form shell 22a (FIG. 2), a middle section or middle form shell 22b (FIG. 3) and a lower section or lower form shell 22c (FIG. 4).

UPPER FORM SHELL 22a

- 45 As shown in FIG. 2, the upper form shell 22a is substantially similar in contour to the upper conduit shell 16a and has a locating member 22a1 (FIGS. 2, 2A) secured to one end of the upper conduit shell 16a (in this case the lower end of the upper conduit shell 22a) by bolts 22a2 and nuts 22a2' and to the upper form shell 22a by a bolt 22a3 and 22a3'. This bolt 22a3 extends through a cover plate 22a4 (FIGS. 2, 2A) on the locating plate 22a1 and an end plate 22a5 (FIGS. 2, 2B) on the lower end of a first section 22a6 (FIGS. 2, 2B) of the upper form shell 22a. The upper end of the first section 22a6 (as viewed in FIG. 2) has an end plate 22a7 (FIGS. 2, 2C) secured by bolts 22a2 and nuts 22a2' to an end plate 22a8 (FIGS. 2, 2D) of a second section 22a9 of the upper form shell 22a. This second section 22a9 is of split half-construction having half-sections 22a9a, 22a9b (FIG. 2D). Each half as shown in FIG. 2 has ears 22a9a1, which ears 22a9a1 are secured together by bolts 22a2 and nuts (not shown in FIG. 2) and has a reinforcing bar 22a9a2 and handles 22a9a3.

55 The locating member 22a1 (FIGS. 2, 2A) and the cover plate 22a4 support the upper form shell 22a, align the upper form shell 22a with the upper conduit shell 16a to define a lining cavity 22a 10 (FIG. 2) between the upper conduit shell 16a and the upper form shell 22a, and close one end of the lining cavity 22a10 (i.e., in this case the lower end, FIG. 2).

ALTERNATIVE EMBODIMENTS

60 It will be understood by those skilled in the art that alternatively, as shown in FIGS. 3, 3A-3E, a middle form shell 22b may be employed.

MIDDLE FORM SHELL 22b

The middle form shell 22b (FIG. 3) has a top locating member or plate 22b1 (FIGS. 3, 3A) secured by welding to a third section (or a first section) 22b2 of the middle form shell 22b as by welding (FIGS. 3, 3A). This locating member 22b1 is secured by bolts 22b3 and nuts 22b4 through a spacer ring 22b5 (FIG. 3) to the flange 16b1 of the middle form shell 16b. It will be noted that the locating member 22b1 is relatively thin to permit cast lining of the lining cavity 22b10 from this upper end of the middle form shell 22b. Beneath the locating member 22b1 a handle 22b6 (FIGS. 3, 3A) is provided. As shown on FIGS. 3, 3B, the third section 22b2 has an end plate 22b7 having bolt holes 22b7a, which holes 22b7a align with bolt holes 22b8a in end plates 22b8 (FIGS. 3, 3C) of a fourth section (or a second section) 22b9 of the middle form shell 22b. Bolts 22b4 and nuts 22b3 secure the plates 22b7, 22b8 together.

As shown in FIGS. 3, 3C, 3D, this fourth section 22b9 has four opposed sections 22b9a hinged together at 22b9b and two of such hinges 22b9b have removable pins 22b9c (FIG. 3C) to permit the facile collapse and removal of such fourth section 22b9.

Referring to the lower portion of the fourth section 22b9 shown in FIGS. 3, 3D, such four sections 22b9a each have a lower end plate 22b11 (FIG. 3D) provided with holes 22b11a, which holes 22b11a register with aligned holes 22b12a (FIG. 3E) in a second alignment member 22b12 to permit securement together of the end plates 22b11 to the second alignment member 22b12 by bolts 22b3 and nuts 22b4. Locating lugs 22b12b on the second alignment member 22b12 engage the spherical ring 16b2 (FIGS. 1, 3) to align the lower end of the middle form shell 22b in the middle conduit section 16b.

LOWER FORM SHELL 16c

As shown in FIG. 4 the lower form shell 22c has a top portion or first portion 22c1, a middle portion or second portion 22c2 and a lower portion or third portion 22c3. For the purpose of securing the lower form shell 22c in the lower portion 16c of the tuyere stock 16 and aligning such lower form shell 22c in such lower portion 16c while permitting access for the castable refractory lining 20 (FIG. 1) in the lining cavity 22c10, a third locating member 22c1a (FIGS. 4, 4A) has its legs 22c1b (FIG. 4A) seated in bifurcated lugs 22c1c (FIG. 4), extending from the sidewalls of the lower sections 16c of the tuyere stock 16. In addition, a bridge 22c1d (FIGS. 4, 4A) of the third locating member 22c1a has its legs 22c1e secured to ears 22c1f (FIGS. 4, 4B) extending from the top section 22c1 of the lower form shell 22c by bolts (not shown) extending through holes 22c1h (FIG. 4) in such ears 22c1f and nuts (not shown). Referring to FIG. 4B, the top section 22c1 is generally round and is provided with a flexing split 22c1j to permit flexing of such top section 22c1. So that the top section 22c1 may be secured to the middle section 22c2, such top section 22c1 is provided at its lower end (as viewed in FIGS. 4, 4B) with a plurality of end sections 22c1 having holes 22c1m (FIG. 4B) therein. These holes 22c1m align with holes 22c2a (FIGS. 4, 4C) in end sections 22c2b (FIG. 4C) in the three split sections 22c2c of middle section 22c2 of the middle portion 22c of the lower form shell 22c, which split sections 22c2c are split at 22c2d (FIG. 4C) and hinged at 22c2e with a removable pin 22c2f therein. Bolts 22c2g (FIG. 4) extend through the holes 22c1m (FIG. 4B) in top section 22c1 and holes 22c2a (FIG. 4C) in middle sections 22c2 and nuts 22c2h (FIG. 4) secure the two sections together. A window 22c2L (FIG. 4) is provided in one of the sections 22c2c for use as hereinafter explained.

FIGS. 4, 4D show three end plates 22c2m in the lower end of the middle section 22c2, substantially identical to the end plates 22c2b in the upper portion of middle section 22c2.

In order to integrate the end plates 22c2m (FIGS. 4, 4D) with end plates 22c3a (FIGS. 4, 4E) of the lower section 22c3, an H-plate 22c3b (FIGS. 4, 4E) is disposed therebetween and is provided with holes 22c3c (FIG. 4E). Bolts 22c3d (FIG. 4) 75

extend through holes 22c2a (FIG. 4D) in end plates 22c2m (FIGS. 4, 4D) holes 22c3c (FIG. 4E) in H-plate 22c3b and holes 22c3d' (FIG. 4) in end plates 22c3a and are secured therein by nuts 22c3e (FIG. 4).

As shown in FIGS. 4, 4F, the lower section 22c3 has three portions 22c3f (FIG. 4E) which are separated by splits 22c3f, two of such portions being hinged at 22c3g by a removable pin 22c3h. The right-hand portion of the lower section 16c of the tuyere stock 16, as viewed in FIG. 4, has a flange 16c1a to which is secured, as by bolts 22c3d and nuts 22c3e, a locating plate 22c3m (FIGS. 4, 4F) having holes 22c3p provided with a locating ring 22c3n fitting over the right-hand portion of the lower section 22c3 of the lower form shell 22c to permit casting of the lining at both ends of the lower form shell 22c.

Referring now to the left-hand portions of FIG. 4, a spiral form 22c4 having a clockwise spiral 22c4a and handle 22c4a' is inserted (clockwise to loosen and then counterclockwise to tighten) into a window 22c4b (FIGS. 4, 4G) in a guide 22c4c (FIGS. 4, 4G) on the peepsite inlet 16c3, (FIGS. 1, 4) and the window 22c2L (FIG. 4) in the middle section 22c2 of the lower mold shell 22c. The guide 22c4c (FIGS. 4, 4G) has locating lugs 22c4d (FIGS. 4, 4G) which lock into bifurcated lugs 22c4e on the inlet 16c3. The guide 22c4c permits cast lining of the refractory 20 through the inlet 16c3 into the inlet lining cavity 22c4f (FIG. 4).

After the refractory lining 20 is cast into the lining cavities 22c10, 22c4f, the locating member 22c1a (FIGS. 4, 4A) is removed and a forming jig 22c5 (FIG. 4H) having a pivot bar 22c5a is seated on the spherical seat 16c1 (FIG. 4) and rotated to form the lining 20 to the configuration indicated by the dotted lines in the upper portion of FIG. 4.

METHOD

35 It will be understood by those skilled in the art from the above description of the form that an improved method is also provided including the steps of:

1. securing the form shell 22 to one end of the conduit shell 40 16 to support the form shell 22, to align the form shell 22 with the conduit shell 16 to define a lining cavity 22a10 (FIG. 2), etc., between the conduit shell 16 and the form shell 22, and to close the one end of the lining cavity 22a10 (FIG. 2), etc., and

45 2. casting a refractory lining 20 in the lining cavity 22a10 (FIG. 2), etc.

SUMMARY OF THE ACHIEVEMENT OF THE OBJECTS OF THE INVENTION

50 It will be recognized by those skilled in the art that the objects of this invention have been achieved by providing an improved form for and method of casting a lining 20 in a conduit 16 having a predetermined nonlinear conduit shell 16, which form 22 is simple and rugged in construction, is readily collapsible and removable from the conduit system after the casting operation, and is reusable in the conduit system during a long operational life for repeated relining of the conduit system.

55 While in accordance with the patent statutes a preferred and alternative embodiment of this invention has been illustrated and described in detail, it is to be particularly understood that the invention is not limited thereto or thereby.

We claim:

1. A form for casting a refractory lining in a conduit having an arcuate conduit shell, said form having:
  - a. a form shell substantially similar in contour to said conduit shell;
  - b. a locating member secured to one end of said form shell to support said form shell, to align said form shell with said conduit shell to define a lining cavity between said conduit shell and said form shell and to close said one end of said lining cavity; and
  - c. said form shell having a first section secured at one end to said locating member and a second section secured at the other end of said first section;

- d. said conduit shell having an inlet and said form shell being provided with a window and having a form in said window, said form and said inlet defining an inlet cavity.
- 2. The form recited in claim 1 and having a guide for said form mounted on said inlet.
- 3. The form recited in claim 1 and having a third section secured to said second section.
- 4. The form recited in claim 1 wherein said second section has three sections and has each section provided with an end

section for securement to said first section, hinge means disposed between two of said three sections, and a removable pin disposed in said hinge means.

- 5. The form recited in claim 3 wherein said third section has three sections and having each section provided with an end section for securement to said second section, hinge means disposed between two of said three sections, and a removable pin disposed in said hinge means.
